[57] CLAIM

The ornamental design for a cabinet latch, as shown and described.

DESCRIPTION

FIG. 1 is a perspective view of the cabinet latch;

FIG. 2 is a cross-sectional view of the cabinet latch taken along line 2-2 of FIG. 1;

FIG. 3 is a front view of the cabinet latch;

FIG. 4 is a side view of the cabinet latch, the other side being symmetrical;

FIG. 5 is a back view of the cabinet latch; and,

FIG. 6 is a top view of the cabinet latch, the bottom view being symmetrical.

The portion of the cabinet latch shown in broken lines forms no part of the claimed design.
